UNITED STATES PATENT OFFICE.

PETER KRUMSCHEID, OF ROXBURY, MASSACHUSETTS, ASSIGNEE OF TWO-THIRDS TO
LEWIS W. KILBOURN, OF CAMBRIDGE, MASSACHUSETTS.

TYPEWRITER.

1,371,694.

Specification of Letters Patent. Patented Mar. 15, 1921.

Application filed March 18, 1916. Serial No. 85,198.

To all whom it may concern:

Be it known that I, PETER KRUMSCHEID, a citizen of the United States, residing at Roxbury, county of Suffolk, Commonwealth of Massachusetts, have invented certain new and useful Improvements in Typewriters, of which the following is a specification.

This invention relates to writing machines for use by the blind, and particularly to a machine for writing Braille and other similar systems wherein the characters are pricked into the paper web in groups of embossed points which are read by touching them with the fingers.

In writing machines of this class, it is desirable that the machine be of light and compact form so as to be capable of convenient transportation upon the person. One object of this invention is to provide a writing machine of this type which may be conveniently carried and operated in the pocket. This object is secured in the present invention by a novel construction and arrangement of feed mechanism whereby the feed

25 of the paper web is accomplished by and in the depression of the embossing key itself so that the machine successively embosses and feeds at each depression of the key. This dispenses with the feed spring and re-

lease mechanism of the ordinary Braille machine, allows the key bars to be materially shortened, and in general enables the machine itself to be made in a much lighter and more compact form. The ordinary

35 Braille machine is further complicated and increased in size by its arrangement for writing single and double base characters.

Another object of the present invention is to provide in a simple and compact form a machine which will write either single or double base, and in which the transition from one to the other may be quickly and easily made.

These and various other features which 45 will appear more fully hereinafter are secured in the machine of the present invention, the construction and operation of which is disclosed in the specification which follows. In the drawings accompanying this 50 specification, a practical embodiment which has been found satisfactory in use is shown. Throughout specification and drawings like reference numerals are correspondingly applied, and in these drawings:

Figure 1 is a plan section of a writing 55 machine in accordance with this invention.

Fig. 2 is a longitudinal section on the line 2—2 of Fig. 1.

Fig. 3 is a vertical section on the line 3—3 of Fig. 1.

Fig. 4 is a detail section of a part of the web feeding mechanism.

Fig. 4 is a sectional view on line 4^a 4^b of Fig. 4.

Fig. 5 is a longitudinal section on the line 5—5 of Fig. 1, and

Fig. 6 is a detail view of the multi-leaf spring for the series of embossing levers, removed.

The various parts of my writing machine 70 are mounted in a suitably shaped case 1, which as here shown is of generally rectangular form, and comprises spaced top and bottom walls, a back wall 15, and connecting end walls. The top wall is preferably removed to permit access to the inclosed parts, and the bottom wall is provided near its forward edge with a vertically disposed partition 2 which extends longitudinally thereof between the end walls of the case, 80 and through which partition the writing and spacer keys of the machine project and are guided.

The paper web W is adapted to be intermittently advanced from a holding magazine H to a receiving magazine R arranged within the case at opposite ends thereof and to be successively pricked or embossed during such feed. Each magazine consists of a portion of the top casing wall and a disk 3 pinned to one end of a revoluble spool 4 upon which the web W is mounted in coiled form. The spools 4 are journaled in bushings 5 sleeved about vertically disposed pins 6 fastened in the top and bottom walls of 95 the case.

The spool of the receiving magazine R is adapted to be rotated at each depression of an embossing key, being provided with a feed ratchet 7 which is integrally formed 100 upon a holder 13 set between the ratchet and the disk 3. Coöperating with the ratchet 7 is a toothed pawl 8 which is connected with a key actuated part 60 of the machine and is normally urged into engagement with 105 the ratchet teeth by a blade spring 9 mounted within the casing. The pawl 8 coöperates with a fixed detent 10, the purpose of

which is to render said pawl inoperative for a tooth space by preventing contact between ratchet 7 and pawl 8 during the initial inward movement of the pawl upon actuation by part 60. A second detent 11 is also provided to prevent back feed of the ratchet 7.

The holder 13 is adapted to be intermittently rotated at each actuation of its ratchet 7 by the feed pawl 8. Loosely mounted 10 within a suitable recess formed internally of the holder is a coil spring 12 one end of which is bent to hook over a pin 12¹ extending from disk 3. Whenever the surface speed of the receiving spool R exceeds that 15 of the feed drum 17, due to the variation in the diameter of the rolls contained on the spools of the respective magazines, the pull of the web, through pin 12¹, causes spring to turn loosely in its holder until the variation 20 is corrected, thus compensating the feed to the constantly increasing surface diameter of the paper roll being wound upon the receiving spool R.

The web W is drawn from the holding 25 magazine H over a guide roll 14 mounted at the right hand corner of the case into a guideway formed by the back wall 15 of the case and an overlying guide strip 16 secured to said wall in spaced relation there- 30 to, being pricked or embossed soon after it enters said guideway.

At the delivery end of the guide-way the web passes over a feed drum 17 revolvably mounted on a shaft 18 journaled within the 35 case. The drum 17 is preferably a rubber-faced roll having a ratchet wheel 17' formed on one end thereof and with which coöperates a feed pawl 19 carried by the key-actuated part 60 of the machine whereby to intermittently rotate said ratchet at each depression of a key. The pawl 19 is normally urged to the ratchet by a blade spring 20 having two spring teeth, one of which engages said pawl 19 and the other of which 40 engages for a similar purpose a second feed pawl 21 for a second feed ratchet 22 formed on the shaft 18 of the feed drum. Each pawl and ratchet mechanism has a detent 23 corresponding in function to the detent 10. 45 A pawl 24 corresponding in function to the detent 11 of the pawl and ratchet mechanism 7-8 engages the teeth of the ratchet 17' to prevent back feed of said ratchet. The pawls 19 and 21 are of different lengths to 50 secure a leverage proportioned to their ratchets.

The purpose of the two ratchet mechanisms 17' and 22 is to allow the machine to be used for writing either single or double 55 base. The teeth of the ratchet 22 are therefore spaced apart angularly twice the spacing of the teeth of the ratchet 17'. Only one ratchet mechanism is used at a time of course, according to whether the machine 60 is writing single or double base, and the

shift from one base to the other is made by means of a shifter 25 which as here shown consists of a plate pivotally mounted at 26 on a suitable bracket 26' fixed within the case and having a shift pin 27 coöperating 70 with the pawl 19 and a shift pin 28 coöperating with the pawl 21. The plate 25 is further provided with a locking notch 29 in which is disposed a locking pin 30 fixed in the case and adapted to lock the plate in 75 one position. The plate is locked in its other position by friction. The plate 25 is shifted manually into either of its two effective positions to throw out of action either one or the other of the pawls 19 and 21, according 80 to which base is to be written.

From the feed drum 17 the web passes to a guide roll 31 and from thence usually to the spool of the receiving magazine. The roll 31 is carried by a bracket 32 which is 85 pivoted at 33 to the case and has at the end a notch 34 in which the free end of a blade spring 35 is disposed to hold the bracket and roll in position and to tension the feeding web.

The end wall of the case adjacent said roll is provided with a slot 36 through which the web may be led should it not be desired to wind it upon the spool of the receiving magazine, as where it is desirable to tear off 95 the web and transcribe the notes thereon as they are made.

The mechanism for pricking or embossing the web as it is fed consists of a series of key-actuated levers 37 arranged below the 100 web and pivoted at their rear ends on a common pivot 38 set in a suitable holder 39 fastened to the inner face of the back walls 15 of the casing. Spring tension is maintained on said lever series by a multi-leaf 105 spring 40 fastened to the inner face of the back wall 15 and having a series of blades (see Fig. 6) corresponding in number to the number of levers and each adapted to bear 110 downwardly upon a lever.

The levers 37 as here shown are six in number, of which three constitute a series for writing single base and all six a series for writing double base. The levers are given the shape best shown in Fig. 5 whereby to position the pins or punches 41 carried at their free ends in the parallel double row relation shown herein and which is the relation for writing the Braille system of characters.

The pins 41 are adapted to be carried into the web W by the depression of the keys, and coöperate with a series of independently adjustable dies 42 disposed on the outer side of the web and carried by the overhanging portion of the anvil 43 which is adjustably secured to the casing. The dies 42 may conveniently be formed as set screws arranged in suitable sockets formed in the anvil and each independently adjustable to compen- 125 130

sate for wear and to regulate the "touch" of the machine. The anvil 43 is itself adjustable transversely with relation to the direction of feed of the web through an elongated 5 slot 44 therein in which fits a screw or other fastening 45 securing the bracket to the case. The anvil is held against lateral movement in either direction by a pin 46 on the case fitting in a notch 47 at the lower edge of the 10 anvil.

Between their ends, the levers 37 are formed each with a ratchet tooth 48 with which teeth engage a series of six ratchets 49, all mounted on a common shaft 50 journaled 15 vertically of the case in suitable bearings. Each ratchet is controlled by a toothed pawl 51 mounted on an oscillatable cam plate 52 pivoted at 53 in the case. The pawls 51 are normally urged into engagement with the 20 ratchets by the fingers of a spring 54 corresponding in shape to the spring 40, and between their ends each pawl is bent as shown leaving a detent spur 55 adapted to engage a throw-off device 56.

Each cam plate 52 is cut-out at one edge, as indicated at 59, providing laterally offset portions 57 and 57'. The inner ends of each of the six key levers 58 are connected to the portions 57 so that one of the cam plates 52 30 will be oscillated in a counter clockwise direction upon a depression of the key of that lever 58 which is connected to said plate.

The oscillation of the cam plates 52 is transmitted to the feed mechanism by a pair 35 of rigidly connected feed actuating plates 60. One of the pins 60' connecting said plates 60 is received in the recess 59 of the cam plates and this pin receives the actuation from the shoulder portion 57' of the 40 particular cam plate 52 which is oscillated and thereby oscillates the plates 60. The plates 60 carry the pawls 8, 19 and 21 and are pivoted for movement about a vertical axis on a common pivot pin 61, being normally urged into said recess 59 by a blade 45 spring 62 fastened to the case and having its free end engaging a pin 63 between said plates. The movement of the plates 60 in their direction of effective swing, which as 50 shown here is clockwise, is stopped by a stop pin 64 suitably arranged with relation thereto.

The feed actuating plates 60 also have movement independently of the cam plates 52 through a pitman 65 operated by a spacer key 66. The pitman 65 has an elongated slot formed at its free end as indicated and in this slot a pin 67 connecting the plates 60 is disposed. The other end of the pitman 60 is fastened at 69 to a bell-crank lever 70 mounted on a rock shaft 71 journaled in a suitable bearing within the case and carrying the key 66.

Each cam plate 52 is actuated by an individual lever of the lever series 58. Each

lever 58 is fastened at its outer end to a bell-crank 72 mounted on an individual rock shaft 73. The shafts 73 are telescopically mounted within each other, the innermost shafts being journaled at their exposed 70 ends in suitable bearings 75 within the case. Each shaft 73 is operated by an individual key 74 which is suitably connected thereto.

In use, the machine may be conveniently carried and operated, if desired, in the 75 pocket. When it is desired to write single base, the pawl and ratchet mechanism 17'-19 is set through the shifter plate 25 to regulate the feed of the web and only the three keys 74 at the right of the space key 80 66 are used. When it is desired to write double base, the shifter 25 is moved thereby, to throw out the ratchet mechanism 17'-19 and to throw in the ratchet mechanism 21-22, and all six keys 74 are used. An actuation of any these keys, through its connection with its cam plate 52 causes said plate to swing counter clockwise on its pivot, drawing the pawl 51 corresponding to the key struck, inwardly and rotating the ratchet 90 49 thereof clockwise one tooth space, thereby causing the particular lever of the lever series 37 actuated by said ratchet to swing upwardly and carrying its pin into the web W to emboss the paper. At the same time, 95 the connected plates 60 are rocked in a clockwise direction on their pivot 61 by the cam surface of the plate 52, drawing the pawl 19 or 21 according to which ratchet mechanism is set for operation, inwardly, and rotating the feed drum counter clockwise one tooth space. The same movement of the plates 60 also draws the pawl 8 for the ratchet of the receiving spool inwardly, rotating that ratchet counter clockwise to 105 wind the strip one tooth space. Should it happen that the strip was being fed out through the slot 36 in the casing, this movement of the receiving spool would, of course, be ineffective.

It will be noted that by this construction the key series is materially shortened in length, inasmuch as but slight leverage is necessary to operate the embossing levers and the feed mechanism. This permits the 115 keys to be arranged within the edge of the case itself, as clearly shown in Figs. 1 and 3, allowing the machine to be conveniently carried within the pocket. The instrument therefore has a very light "touch" and is 120 practically noiseless in operation. By dispensing with the strong feed spring and associated mechanism thereof, a considerable economy of space is effected, and the structure of the machine correspondingly simplified.

Various modifications in the form and construction of this invention may obviously be resorted to, within the limits of the appended claims.

What I therefore claim and desire to secure by Letters Patent is:

1. In a typewriter, a strip, a strip embossing mechanism, a strip feeding and winding mechanism, a key, operative connections from said key to said strip embossing mechanism including a member mounted for movement in one direction and effective in the initial depression of the key to actuate 5 the strip embossing mechanism, and operative connections from said key to said feeding and winding mechanism including a member mounted for movement in a direction opposite to said first-named member 10 and effective in the continued depression of the key to actuate said strip feeding and winding mechanism.
2. In a typewriter, an impression strip, an impression mechanism including a plurality 20 of impression levers having embossing elements, a ratchet for each lever, a pawl for each ratchet, and key operated means for actuating each of said pawls.
3. In a typewriter, an impression strip, an impression mechanism including a plurality 25 of impression levers having embossing elements, a ratchet for each lever, a pawl for each ratchet, key-operated means for actuating each of said pawls, and a feed mechanism actuated by said means in the operation thereof.
4. In a typewriter, an impression strip, an impression device, an actuating mechanism therefor, including a key-operated oscillatable member, a feed mechanism, an actuating mechanism therefor including a member oscillated by said first-named member in the operation thereof, means for actuating 35 said oscillatable feed member independently of said impression device actuating member, and means for selectively varying the feeding relation of said feed mechanism.
5. In a typewriter, an impression strip, an impression device, an actuating mechanism therefor including a key-operated oscillatable member, a feed mechanism including 45 two sets of pawl and ratchet devices adapted to be selectively moved into feeding relation, an actuating mechanism for said feed mechanism including a member oscillated by said first-named member in the operation thereof, and a shifter for selectively moving a set of said pawl and ratchet devices into feeding 50 relation to said feed mechanism.
6. In a typewriter, an impression strip, an impression mechanism, key-operated means for actuating said mechanism including a member mounted for actuating movement in one direction, a feed mechanism for said 55 strip, and an operating mechanism for said feed mechanism including a member mounted for actuating movement in a direction opposite to the direction of movement of said first-named member and actuated by said 60 member.
7. In a typewriter, an impression strip, an impression mechanism, key-operated means for actuating said mechanism including a member pivoted for actuating movement in one direction, a feed mechanism for said strip, an operating mechanism for said feed mechanism including a member pivoted for actuating movement in a direction opposite to the direction of actuating movement of said first-named member and actuated by 70 said member in the effective movement thereof, and means for actuating said feed member independently of said impression member.
8. In a Braille typewriter adapted to write 80 both single and double base, selectively, a strip, a strip embossing mechanism, a strip feeding and winding mechanism including two sets of independently effective pawl and ratchet devices adapted to be selectively 85 moved into feeding relation to the strip according to the desired base, key-operated means for actuating said embossing mechanism and said feeding and winding mechanism, and a shifter for selectively coupling 90 the respective pawl and ratchet of a set.
9. In a Braille typewriter adapted to write both single and double base, selectively, a strip, a strip embossing mechanism, a strip feeding and winding mechanism including two independently effective devices 95 adapted to be selectively connected in feeding relation to the strip, means for selectively moving one or the other of said devices into said relation, and key operated 100 means for actuating said embossing mechanism and said feeding and winding mechanism.
10. In a typewriter, an impression strip, a feed drum, a shaft therefor, a ratchet on 105 said drum and a ratchet on said shaft, pawls for each ratchet, means for selectively coupling one pawl and one ratchet of a pair to feed said strip, and means for operating said selected pawl.
11. In a typewriter, an impression strip, a feed drum, a shaft therefor, a ratchet on 110 said drum and a ratchet on said shaft, pawls of different lengths for each ratchet, a manually shiftable device having two pins disposed each for engagement with a pawl for selectively coupling one pawl and one ratchet to feed said strip, and key-actuated means for operating said selected pawl.
12. In a typewriter, a perforation strip, 120 a perforating mechanism, a key, an oscillatable member operated by said key and operating said perforating mechanism, a strip feeding and winding mechanism, and an oscillatable member operated by said first-named member during the continued downward depression of the key and operating said feeding and winding mechanism.
13. In a typewriter, a casing, a perforation strip, strip feeding and winding mech- 130

anism and strip perforating mechanism located within the casing, an oscillatable member, a member oscillated thereby, operative positive connections from said member 5 to said feeding and winding mechanism and to said perforation mechanism, respectively, a plurality of telescopically mounted rock shafts located within the casing and operatively connected with said oscillatable member, and a key for each shaft.

14. In a typewriter, a strip, winding and feeding mechanism for said strip, a plurality of strip embossing elements, and a mount for a plurality of dies and adjustable relative to said strip, said dies individually adjustable in said mount and consisting of screws having sockets adapted to receive said embossing elements.

15. In a typewriter, a strip, strip winding and feeding mechanism, a plurality of strip embossing elements, a die mount adjustable transverse to the direction of travel of said strip, and a plurality of individual adjustable dies carried by said mount and 25 having sockets to receive said embossing elements.

16. In a writing machine, an impression strip, strip embossing mechanism, an actuator for said strip embossing mechanism, strip feeding mechanism, an actuator for said strip feeding mechanism operated by and in the movement of said actuator for the strip embossing mechanism, and a key directly connected to said actuator for the 30 strip embossing mechanism to actuate said strip embossing mechanism and effective through said actuator to operate the actuator for the strip feeding mechanism.

17. In a writing machine, an impression strip, strip embossing mechanism, including a plurality of embossing points adapted to be carried into writing contact with said strip, an actuator for said strip embossing mecha-

nism, strip feeding mechanism, an actuator for said strip feeding mechanism operated 45 by and in the movement of said actuator for the strip embossing mechanism, and a key directly connected to said actuator for the strip embossing mechanism to actuate said embossing mechanism and effective 50 through said actuator to operate the actuator for the strip feeding mechanism.

18. In a typewriter, an impression strip, strip embossing mechanism, an actuator for said strip embossing mechanism, strip feeding mechanism, an actuator for said strip feeding mechanism operated by and in the movement of said actuator for the strip embossing mechanism, and a key directly connected to said actuator for the strip embossing mechanism, to actuate said embossing mechanism and effective through said actuator to operate the actuator for the strip feeding mechanism, and a second key directly connected to said actuator for the 55 strip feeding mechanism for operating said strip feeding mechanism independently of said strip embossing mechanism.

19. In a pocket machine for writing Braille, a casing adapted to fit within the 70 pocket, a strip movable relative to said casing, strip feeding mechanism mounted within said casing, strip embossing mechanism mounted within said casing and including a plurality of embossing devices 75 adapted to be carried into writing contact with the strip, and an operating mechanism for said strip feeding and embossing mechanisms including a plurality of telescopically mounted rock shafts journaled within 80 the casing and operatively connected with said feeding and embossing mechanisms, and a key for each shaft disposed within the casing edge.

In testimony whereof I affix my signature. 85
PETER KRUMSCHEID.
